UNITED STATES PATENT OFFICE.

CHARLES ACKROYD, OF LOS ANGELES, CALIFORNIA.

TRAMMEL.

Application filed April 20, 1926. Serial No. 103,298.

My present invention has to do with instruments of precision, and contemplates the provision of a trammel that is simple and inexpensive in construction, is susceptible of ready adjustment, is efficient in use, and, in general, is well adapted to withstand the usage to which devices of corresponding character are ordinarily subjected.

With the foregoing in mind, the invention in all of its details will be fully understood from the following description and claims when the same are read in connection with the drawings, accompanying and forming part of this specification, in which:—

Figure 1 is a broken side elevation of the trammel constituting the best practical embodiment of my invention of which I am cognizant.

Figure 2 is a detail longitudinal section taken in the plane indicated by the line 2—2 of Figure 3.

Figure 3 is a transverse section with parts in elevation.

Figure 4 is a detail perspective of the spring shoe comprised in the device.

Similar numerals of reference designate corresponding parts in all of the views of the drawings.

Among other elements my novel device comprises a body bar 1, of steel or other appropriate material. The said body 1 is provided upon one of its edges with fine teeth 2 and is provided on its face with a graduated scale 3.

In addition to the body bar 1 the trammel includes a point 4 designed to be adjustably fixed with respect to the bar 1, and a point 5 that is equipped for quick and easy adjustment on the bar 1 in the direction of the length thereof and is also adapted to remain in the position in which it is placed as hereinafter described.

The point 4 is provided with an enlargement 6 that straddles and is slidable upon the body bar 1, and in the bight portion of the enlargement 6 is arranged a shoe 7 with upturned ends, the said shoe being designed to be pressed against one edge of the body bar 1 through the medium of a screw 8 threaded through the wall at the top or heel end of the enlargement 6. Manifestly by tightening the screw 8 the point 4 may be adjustably fixed to the bar 1, and after the screw 8 is loosened to lessen the frictional contact between the shoe 7 and the bar 1, the pointer 4 may be readily adjusted on

the bar 1 in the direction of the length thereof. It will also be understood that the enlargement 6 snugly receives the bar 1 and therefore the point 4 is held against movement with respect to the bar 1, other than the longitudinal movement alluded to.

The point 5 is provided at its upper end with an enlargement 9 that straddles the body bar 1 from below and is provided in one of its walls with an aperture 10, preferably of V-shape as illustrated. The said enlargement 10 carries a pointer 11 arranged in the vertex of the aperture 10, and arranged within the enlargement 9 and against the lower edge of the body bar 1 is a spring shoe 12 which is normally in the state shown in Figure 4, and hence when interposed between the lower portion of the enlargement 9 and the body bar 1 is adapted to exert yielding pressure against the lower edge of the body bar 1. The said resilient shoe 12 is provided at its middle with a pendent loop 13 that is disposed in a pocket 14 in the enlargement 9, as shown in Figure 2.

Surmounting the enlargement 9 and connected thereto through the medium of screws 15 is a crown block 16, and in confronting portions of the enlargement 9 and the crown block 16 are bearings 17 for a shaft 18, the said shaft 18 being equipped with a spur gear 19 in mesh with the teeth 2 and having at one end a knurled finger wheel 20 and at its opposite end a threaded portion to receive a binding wheel 21 with a washer or washers between it and the adjacent side of the enlargement 9 and crown block 16 whereby when the wheel 21 is tightened the point 5 will be adjustably fixed with respect to the body bar 1 while when the wheel 21 is loosened, the shaft 18 may be turned through the hand wheel 20 for the movement of the point 5 on the body bar 1 in the direction of the length thereof.

It will be apparent from the foregoing that in addition to constituting an efficient and otherwise advantageous trammel, my novel device may be used to advantage as a scale and as a straight edge.

I have entered into a detailed description of the construction comprised in the device constituting the best practical embodiment of my invention in order to impart a full, clear and exact understanding of the said embodiment. I do not desire, however, to be understood as limiting myself to the precise construction and arrangement disclosed,

my invention being defined by my appended claims within the scope of which modifications may be made without departure from my invention.

Having described my invention, what I claim and desire to secure by Letters Patent, is:—

1. In combination, a body bar having a toothed edge and also having a graduated scale on its face, a point disposed at an angle to the body bar and having an enlargement straddling said bar and also having a V-shaped opening in one of its walls and a pointer in line with the axis of said point and projecting into said V-shaped opening at the vertex thereof, a crown block connected to said enlargement, a spring shoe interposed between the said enlargement and one edge of the body bar, and a shaft journaled between the said enlargement and the said crown block and having a toothed portion in mesh with the teeth of the bar and also having a finger piece for the ready turning thereof; the said enlargement having a pocket, and the said shoe having a pendent loop-shaped portion at an intermediate point in its length and disposed in said pocket.
2. In combination, a body bar having a toothed edge and also having a graduated scale on its face, a point disposed at an angle to the body bar and having an enlargement straddling said bar and also having a V-shaped opening in one of its walls and a pointer in line with the axis of said point

and projecting into said V-shaped opening at the vertex thereof, a crown block connected to said enlargement, a spring shoe interposed between the said enlargement and one edge of the body bar, and a shaft journaled between the said enlargement and the said crown block and having a toothed portion in mesh with the teeth of the bar and also having a finger piece for the ready turning thereof; the said enlargement having a pocket, and the said shoe having a pendent loop-shaped portion at an intermediate point in its length and disposed in said pocket.

3. In combination, a body bar having a toothed edge and also having a graduated scale on one of its sides, a spring shoe bearing against the opposite edge of the bar, a point having a portion straddling the spring shoe and the bar and apertured to hold the spring shoe, pointer means also carried by said point and adapted for co-operation with the graduated scale, a finger operated shaft carried by the point and having a toothed wheel in mesh with the teeth of the bar, and a second point receiving and adjustable on the bar in the direction of the length thereof and equipped for adjustable fixture to the bar.

In testimony whereof I affix my signature.

CHARLES ACKROYD.
